CORPORATION OF MASSACHUSETTS

METHOD OF AND MECHANISM FOR COATING ROOFING ELEMENTS

Application filed March 22, 1927. Serial No. 177,407.

This invention relates to a method of making thick butt fabricated roofing elements which are characterized by having the butt portion, which is exposed to the weather when laid, completely covered both on its exposed face and edges with a continuous coating of asphalt preferably masked by a surfacing layer of grit or its equivalent. Roofing elements of this type are customarily made of material comprising a felted fibrous base which is comparatively bibulous. This felted material in sheet form is thoroughly saturated with waterproofing material such as low melting-point asphalt. The saturated sheet is thereupon coated on both sides with a layer of relatively high melting-point oxidized asphalt which is particularly suited for weather-proofing the roofing material and preventing the access of moisture to the fibers of the saturated base. In order to protect the exposed coating of asphalt which is liable to deterioration by effects of the weather, such as rays of the sun, which tend to polymerize the asphalt and render it brittle and subject to cracking, a surfacing layer of comminuted mineral matter is applied to the coating on one or both sides of the sheet to mask and protect the coating from effects of the weather. The finishing layer of mineral matter also performs other useful functions such as adding to the decorative effect of the roofing unit and weighting the exposed portions to counteract tendencies to curl or to be lifted by the action of wind. From sheet roofing material thus prepared, the roofing elements are customarily cut out in any desired shapes and are packaged as a finished article for shipment and subsequent use. Such elements, however, have objectionable features in that the cut edges along the butt of the element expose cut ends of fibers to the weather. These cut ends being unprotected have been found to absorb moisture in wet weather and to permit the access of oxygen to the thin films of asphalt with which the fibers of the base are coated. As a result of changes of moisture content and exposure to air, the asphalt-saturated base swells or bulks, and the asphalt becomes oxidized and polymerized, resulting eventually in a breaking off of portions of the coating asphalt and mineral surfacing. The rate of such deterioration increases progressively inasmuch as the further it goes, the more exposed is the roofing element to the deteriorating effects of the weather.

Another objectionable feature to roofing elements cut from a sheet of roofing material made as described above is that such material is comparatively thin and when elements cut therefrom are laid upon a roof, the roof as a whole presents a flat and unsubstantial appearance, which is not in keeping with such buildings as residences of the better kind. Hence discriminating architects have largely avoided the ordinary asphalt roofing elements in the construction of the better class of residences on account of the unfavorable appearance often presented thereby.

In order to overcome the objections to the ordinary roofing elements cut from asphalt coated sheet material, it has been found that if such elements are provided with an additional coating of asphalt over the portion of the element which is exposed to the weather when laid, including the butt and side edges, such an additional coating serves both to seal the edges which were previously a vulnerable point of the element, and also to thicken the visible portion of the element in such a way as to give a roof upon which such elements are laid a substantial appearance. This invention relates to a method of and means for applying such an additional coating of asphalt to pre-cut roofing elements which have been made as described above, and applying an additional surface layer of comminuted mineral matter, such as crushed slate or the like, to the protective asphalt coating thus applied.

According to my invention, I have devised apparatus for applying in a novel way to roofing elements cut to shape from finished sheet roofing material, an additional coating of molten asphalt over the face and edges of the elements which will be exposed to the weather when laid, surfacing the additional coat with a layer of comminuted mineral material, and operating on the elements thus treated to press the mineral particles into

firm engagement with the asphalt coating and at the same time to shape the thickened butt portion of the shingle as desired.

In carrying out my novel method, I arranged pre-cut roofing elements in a continuous overlapping series, in which each element is partly overlaid by other adjacent elements in the series. Preferably the unlapped portion of each element will be substantially the same as the portion of the element which will be exposed to the weather when the element is laid with others on a roof. Upon the unlapped face portions and edges of the elements in the series is applied a continuous coating of suitable waterproofing material such as certain asphalts commonly used for coating purposes. Grit or the like may be applied to the coating while still hot and sticky, and the elements are separated before the coating sets or hardens.

This method of applying coating to elements in lapped series may be used to build up butt portions of extra thickness tapering off toward the head. This may be done by arranging the elements so that only a small part of the butt portion of each is unlapped in the series. After these have been coated, with or without the addition of grit, the elements may be separated further and a second coating applied. This may be repeated until the whole portion of each element which will be exposed to the weather when laid is coated, whereupon the elements are separated and further treated as hereinafter described. This results in an element having a number of extra coatings at the butt edge extending toward the head, each such coating except the top one being overlaid by a coating extending further toward the head of the element.

Various advantageous features of the invention will be apparent to one skilled in the art from the disclosure of the invention in the following description and on the drawings of which—

Figure 1 represents diagrammatically a side elevation of an embodiment of my invention.

Figure 2 is a plan view of the same.

Figures 3 and 4 are detail views of a portion of Figure 1, shown on a larger scale.

Figure 5 illustrates the action of certain elements on the butt portion of the roofing elements.

Figure 6 is a perspective of a roofing element after being passed through the mechanism illustrated in Figure 1.

Figure 7 is a diagrammatic side elevation of a modified form of apparatus.

Figure 8 is a plan view of the same.

Figures 9 and 10 are detail views of portions of Figure 7, shown on a larger scale.

Figure 11 is a side elevation of a portion of the mechanism illustrated in Figure 8.

Figure 12 is a section taken on the line 12—12 of Figure 11.

Referring to Figure 1, a series of roofing elements 20 are fed to the mechanism as on a conveyor 21. The elements are placed on this conveyor in an overlapping relation either by hand or by any suitable mechanism (not shown). Preferably, although not necessarily, the elements may be pre-heated before being so arranged and/or the unlapped surfaces may be heated after the elements have been arranged in overlapping series as by a steam box 22, a blast of hot air or any other suitable and convenient means. From the conveyor 21, the series of elements 20 may be transferred to another conveyor 23 without altering their relative relation. Inasmuch as roofing elements of the common asphaltic type are somewhat flexible and have a rough surface due to the surfacing layer of grit, the relative relation between successive elements placed in an overlapping relation as shown will not easily be disturbed except by positive means operating for that purpose. As indicated in Figures 3 and 4, the elements 20 are overlapped upon each other in such a way that each element is covered by the next overlying element by approximately the same amount and at substantially the same portions thereof as the element will be overlaid when in place on a roof, so that the uncovered portion as shown in Figures 3 and 4 represents substantially the portion to be exposed to the weather when the element is laid on a roof. In this form of the apparatus, the elements are shown as being advanced butt edge first, each element being partly overlaid by elements following it. The conveyor 23 which receives the series of elements may be disposed horizontally if desired, but as shown on the drawing it is inclined downwardly (the angle of inclination being somewhat exaggerated on the drawing for the purpose of illustration) and passes beneath suitable means for applying to the succession of elements carried by the conveyor heated asphalt in sufficient quantity to coat completely the exposed surfaces and edges of the elements with a continuous film of asphalt, and means for showering the freshly coated surfaces with comminuted mineral such as crushed slate or the like. In order to apply an even coating to the exposed surfaces of the elements, I may provide a suitable receptacle 24 for molten asphalt, this receptacle having therein heating units 25 if desired. One side edge of the receptacle 24 is preferably cut lower as at 26 than the other edges, a feeding guide 27 being secured thereto in order to feed a sheet of molten asphalt from the receptacle 24 down to close proximity to the surfaces to be coated, this guiding means 27 being used to prevent the sheet from breaking up into driblets under the action of surface tension, and thus to insure an

even application of the asphalt under the entire exposed surfaces of the elements. The guide 27 may be of any preferred construction. As shown, it comprises a piece of wire netting having meshes of suitable size, the netting serving to hold the flowing asphalt in a continuous sheet. In order to prevent premature cooling of the asphalt as it flows along the guide 27 in a thin sheet, a steam box 28 or other heating means may be provided in juxtaposition thereto, this heating means being available to regulate the temperature and hence the viscosity of the asphalt at the moment it is deposited on the elements 20. Immediately following the asphalt container 24 may be located a suitable hopper 29 from which a shower of grit or other comminuted material may be continuously deposited upon the freshly applied coating of asphalt by mechanism well known in the art. If desired, such surfacing material may be heated as by suitable units 30 placed within the hopper to insure firmer engagement of the grit particles with the asphalt. The elements thus coated and surfaced on the conveyor 23 may then be separated and transferred to another conveyor 31. In order to separate the elements, I may provide a roll 32 adjacent to the delivery end of the conveyor 23, the roll 32 being resiliently supported to press on the successive elements. This roll is preferably driven at a peripheral speed equal to that of the conveyor 23. Another roll 33 may be yieldingly supported to engage the elements at a point adjacent to the receiving end of the conveyor 31, this roll and the conveyor 31 being preferably driven at an equal peripheral speed greater than that of the roll 32 and the conveyor 23. The rolls 32 and 33 may be so spaced that when the butt edge of a roofing element enters the nip between the roll 33 and the conveyor 31, the upper or head edge of that element will have cleared the roll 32. The next following element, however, which overlies the element entering the nip of the roll 33 is at this point still between the slower moving roll 32 and conveyor 23, so that the faster feeding action of the roll 33 and conveyor 21 pulls the element entering the nip between them away from the series on the conveyor 23 and thus spaces them as indicated in Figure 1. The rolls 32 and 33 in addition to separating the successive elements also serve to press the grit lying on the fresh coating on the faces of the elements into more intimate embedded contact with the asphalt. The elements on the conveyor 31 may then be discharged edgewise one after the other to a suitable conveyor 34, guiding plates 35, 36 being provided as desired for insuring the proper upright positioning of each element on the conveyor 34. Suitable means may be provided for shaping and finishing the additional coating and surfacing layers which have been applied to the face and edges of the butt portion of the elements. Such apparatus may be as illustrated in Figures 1 and 2, and may comprise a pair of vertically arranged endless belts 37, 38 between which the elements are deposited from the conveyor 31. These belts 37, 38 are preferably arranged to converge so that at their delivery end, the butt portion of each element is pressed between their opposing faces as they pass between the rolls 39, 40 which are preferably yieldingly mounted and adjustable both as to axial direction and distance apart. At the same time, the weight of the element on the conveyor 34 serves to press the grit adhering to the butt edges of the element into more intimate contact with the coating on the edges. If desired, the axes of the rolls 39, 40 may be inclined toward each other slightly so that the pressing faces of the belts 37, 38 which pass between them will also converge upwardly. This tends to impart a taper to the thickened butt portion of the roofing element as indicated at 41 in Figure 6. In this figure also are shown narrow tongues of asphalt and grit extending upwardly from the butt portion, these being occasioned by the slots in the element which overlapped this one in the series during the application of the asphalt and grit. Slotted elements are shown in the drawing merely by way of example, such elements having a shape widely used in the trade. It is obvious that the process and apparatus are not limited to such a shape, and that if the slots were eliminated or replaced by grooves or the like, the additional coating applied by the present method and apparatus would be limited substantially to the portion of the face and edges to be exposed to the weather when the element is in position on a roof.

A modified form of the apparatus as a whole is illustrated in Figures 7 to 12. According to this embodiment of the invention, the conveyor 21 feeds to the conveyor 23 a series of roofing elements overlapped in the opposite direction to that shown in Figure 1, that is, the elements are fed head first instead of butt first, with the head portions thereof overlapped by the next element ahead, rather than by the next following. In this case, I prefer to slope the conveyor 23 upwardly so that the asphalt when applied as illustrated in Figure 9 will tend to flow toward the butt edges of each element. It is obvious, however, that if desired, the conveyor 23 may be level either in the form of apparatus shown in Figure 1 or that shown in Figure 7. The coating device in the apparatus illustrated in Figure 7 may be identical with that illustrated in Figure 1. The grit-applying device 29 may also be the same, as well as the rolls 32 and 33 which separate the overlapped shingles from one another. The separated shingles are discharged head

first on a conveyor 34 which carries them off at right angles to their motion on the conveyors 23 and 31, as shown in Figure 8. Since in this case the butt portions of the elements are uppermost as the shingles are conveyed edgewise on the conveyor 34, the belts 37, 38 and the rolls 39, 40 about which the belts pass are elevated sufficiently to engage the butt portions of the elements passing therebeneath. As indicated in Figure 12, the axes of the rolls 39, 40 may be inclined so as to diverge upwardly and to tend to taper the thickened butt portions of the elements which pass between them. The butt edges of the elements may at the same time be shaped as desired. As indicated in Figures 11 and 12, a suitable roller 49 may be mounted to press its edge against the butt edge of elements passing between the rolls 39, 40. As shown in Figure 12, the roll 49 may have a grooved edge 50 to round off the butt edge of the elements, but it is obvious that they may be shaped in any desirable way by shaping the edge of the roll 49 accordingly.

The method of thickening the butt portions of roofing elements and sealing their butt edges as herein described is a simple and effective way of applying the second coating of asphalt and surfacing with grit to the exposed faces and edges of the roofing elements which readily lends itself to the apparatus described. By this means and method, the extra asphalt and grit are applied only to those portions of the shingle which need additional protective coating, and the second coating of asphalt is made to envelop the cut edges of the element at its butt portion and to join the original asphalt coating, if there be one, on the under face of the element to seal the edges of the butt portion and to form a complete envelope enclosing the entire portion of the shingle which is exposed to the weather when laid.

Having thus described certain embodiments of this invention, it should be evident to those skilled in the art that various changes and modifications may be made therein without departing from its spirit or scope as defined by the appended claims.

50 I claim:—

1. The method of coating the face portion and edges of roofing elements, which are to be exposed to the weather when the elements are laid on a roof, which comprises arranging the elements in a series wherein the elements are in successive overlapped relation leaving only said face portion and edges of each element unlapped, flowing a continuous stream of coating onto the face and edges of the unlapped parts of said series of overlapped elements, and separating the individual elements from the series.

2. The method of coating the face portion and edges of roofing elements, which are to be exposed to the weather when the elements

are laid on a roof, which comprises arranging said elements in a series in successively overlapped relation, conveying the overlapped elements lengthwise of the series past a given point, and flowing on said series of elements at said point a continuous stream of molten asphalt extending transversely across the series.

3. Steps in the method of making thick-butt roofing elements, which comprise arranging a series of elements in successive overlapped relation such that each element is lapped and substantially covered by adjacent elements except for the face portion and edges to be exposed to the weather when the element is laid on a roof, flowing a continuous stream of waterproofing material onto the uncovered portions of the elements, surfacing said coating with comminuted material, and separating the individual elements.

4. Steps in the manufacture of roofing elements, which comprise arranging a series of elements in successive overlapping relationship, applying waterproof coating material to said elements while so arranged, surfacing the coated portions with comminuted material, separating the individual elements, and thereafter applying pressure to said surfaced portions.

5. Steps in the method of making thick-butt roofing elements, which comprise arranging a series of elements in successive overlapped relation such that each element is lapped and substantially covered by adjacent elements except for the face portion and edges to be exposed to the weather when laid on a roof, applying a continuous coating of molten asphalt to the uncovered portions of the elements, covering said asphalt coat while hot and sticky with granular material, separating the individual elements, and pressing the coated face and edges of each element.

6. Steps in the method of making thick-butt roofing elements, which comprise arranging elements cut to shape from sheet roofing material of felted fibrous stock saturated and coated with asphalt and surfaced with granular mineral matter in an overlapping series such that each element is substantially lapped and covered by adjacent elements except for the portion of its face and edges to be exposed to the weather when the element is laid on a roof, feeding the

elements such that the head portion of each element is covered by the butt portion of another element, applying progressively to the uncovered surfaces a continuous coating of molten asphalt, showering granular mineral matter on said coating while still hot and sticky, separating the individual elements successively from the series, and pressing the freshly coated surfaces of the elements.

7. Apparatus of the class described, com-

70

prising means for applying a continuous film of molten asphalt to the exposed face and edge portions of a series of lapped roofing elements, means for surfacing said film with granular mineral matter, means for thereafter separating said elements successively from the series, and means for pressing said face and edge portions.

8. Apparatus of the class described, comprising means for conveying a series of roofing elements in overlapping relationship, means for applying a continuous film of molten asphalt to the exposed surfaces of the elements in said series, means for covering said film with grit, means for separating the elements successively from the series, and means for molding the butt portions of the separated elements including the butt edges.

9. The method of coating a roofing element, which comprises covering a portion of a face of a roofing blank with another roofing blank, covering the remaining portion of the face and adjacent edges with a coating of liquefied asphalt, and separating said blanks.

25 In testimony whereof I have affixed my signature.
